UNITED STATES PATENT OFFICE.

ANDRÉ LAVAULT, OF PARIS, FRANCE, ASSIGNOR TO ASSOCIATED MERCHANTISING CORPORATION, A CORPORATION OF NEW JERSEY.

DESIGN FOR A BOX FOR PERFUME, POWDER, OR THE LIKE.

Application filed November 25, 1927. Serial No. 24,275. Term of patent 14 years.

To all whom it may concern:

Be it known that I, ANDRÉ LAVAULT, a citizen of France and a resident of Paris, France, have invented a new, original, and ornamental Design for a Box of Perfume, Powder, or the Like, of which the following is a specification, reference being had to the accompanying drawing, forming part thereof.

In carrying out my design, the rectangles on the sides of the box and the triangles on the top of the box are of green and gold color alternately.

I claim:

The ornamental design for a box for perfume, powder, or the like, as shown and described.

A. LAVAULT.
